(57) **CLAIM**

The ornamental design for a chair, as shown and described.

DESCRIPTION

FIG. 1 is a perspective view from the front side of a chair.
FIG. 2 is a perspective view from the rear side thereof.

FIG. 3 is a front elevation view thereof.

FIG. 4 is a right side elevation view thereof. A left side elevation view is omitted because it is a mirror image of the right side elevation view.

FIG. 5 is a top plan view thereof.

FIG. 6 is a rear elevation view thereof.

FIG. 7 is a bottom plan view thereof.

FIG. 8 is a cross sectional view thereof taken along Line 8-8 in FIG. 3.

FIG. 9 is a cross sectional view thereof taken along Line 9-9 in FIG. 3.

FIG. 10 is a perspective view thereof with the upper part of the backrest flat.

FIG. 11 is a perspective view thereof with the lower part of the backrest folded up and the upper part of the backrest folded forward; and,

FIG. 12 is a perspective view thereof with the lower part of the backrest folded up and the upper part of the backrest folded backward.

The portions of the chair shown in broken lines are for the purpose of showing environmental structure only and form no part of the claimed design.
